UNITED STATES PATENT OFFICE.

MARTIN L. WIENER, OF AKRON, OHIO, ASSIGNOR TO THE OLDFIELD TIRE COMPANY,
OF CLEVELAND, OHIO, A CORPORATION OF OHIO.

DESIGN FOR A PNEUMATIC TIRE.

57,290.

Specification for Design.

Patented Mar. 8, 1921.

Application filed July 29, 1920. Serial No. 339,906. Term of patent 14 years.

To all whom it may concern:

Be it known that I, MARTIN L. WIENER, a citizen of the United States, residing at Akron, in the county of Summit and State of Ohio, have invented a new, original, and ornamental Design for Pneumatic Tires, of which the following is a specification, reference being had to the accompanying drawings, forming a part thereof.

In the drawings, Figure 1 is a plan view of a portion of a tire showing by new design.

Fig. 2 is a cross section on the line 2—2 of Fig. 1.

I claim:

The ornamental design for a pneumatic tire, as shown.

MARTIN L. WIENER.
